UNITED STATES PATENT OFFICE

2,316,270

PRESELECTOR

Edward J. Mastney, Berwyn, Ill., assignor to Oak
Mfg. Co., Chicago, Ill., a corporation of Illinois

Application August 7, 1942, Serial No. 453,975

1 Claim. (Cl. 74—10)

This invention relates to a preselector and particularly to an improvement thereon for adjusting the same. The preselector proper is generally of the type shown in my Patent 2,161,183, granted June 6, 1939.

The invention will be described with reference to the drawing wherein Figure 1 shows an elevation partly in section of the pre-selecting mechanism. Figure 2 is a side view of a pre-selector unit in a normal position. Figure 3 is a sectional elevation of one end of the preselector unit and specifically showing the invention herein claimed. Figure 4 is an exploded view of the manual adjustment of the preselector unit.

A base 10 has mounted thereon a gang condenser frame 11 supporting stator plates 12. Rotatively mounted on frame 11 is a condenser shaft 13 carrying rotor plates 14 cooperatively associated with the stator plates. This gang condenser is an example of a device which is to be turned to predetermined positions. The mechanism for doing this is mounted upon base 10 and includes a pair of supporting plates 15 and 16 bolted to base 10.

Rotatively mounted in plates 15 and 16 is a shaft 17. One end of shaft 17 is rotatively coupled to condenser shaft 13 by a suitable universal joint means 18. Shaft 17 is provided with sleeves 19 and 20, both alike. As clearly shown, these sleeves have shoulder portions 21 and 22 bearing on the inside faces of plates 15 and 16 and in effect constituting end thrust sleeves. The shoulder ends of these sleeves are preferably so fabricated as to provide a small annular clearance 23 around shaft 17.

Between sleeves 19 and 20 are five identical control units 25-29 inclusive. Referring to unit 29, as an example, there is provided a center washer 30 snugly fitting shaft 17. As shown in the corresponding washer 30' of unit 28, the center washer is provided with a radially extending finger 31'. On opposite sides of center washer 30 are sleeves 32 and 33 having the same general construction as sleeves 19 and 20. Thus sleeve 32 has a cylindrical portion 35 extending to a shoulder 36 and then an enlarged cylindrical portion 37. Enlarged cylindrical portion 37 is so shaped on the interior that an annular region 38 is provided around shaft 17.

Sleeve 33 is the image of sleeve 32 and is provided with the same details. Rotatively mounted on reduced cylindrical portion 35 is a washer 40 having a finger similar to finger 41' on washer 40' of unit 28. As clearly shown in unit 28, finger 41' is bent over to lie in the path of travel of

finger 31' of the center washer. Beyond this washer 40 is a gear 42 provided with a finger 43 bent over to lie in the path of travel of finger 41' of the adjacent washer. Sleeve 33 is similarly provided with a washer and gear.

Each unit is controlled by a pair of offset racks 50 and 51 (see unit 28) engaging the gears 42 and 42' of each unit and disposed on opposite sides of shaft 17. These two racks are carried by a lever 52. It is clear that upon downward movement of the two racks, the two gears of a unit will be urged in opposite directions. Assuming center washer 30 is fixed relative to shaft 17, then each unit will tend to cause shaft 17 to wave to a predetermined position upon downward movement of the racks. This is more fully explained in the patent referred to herein.

In order to guide each lever and rack means, a top plate 55 is carried by side plates 15 and 16 as by ears 56. Plate 55 is slotted to journal lever 52. Additional strengthening members 57 and 58 extend between side plates 15 and 16 to provide a rigid structure. Each lever 52 may have a button 60 fitted thereon.

As is evident, the operation of the device requires that each center washer 30 of a unit be fixed relative to shaft 17. In addition, to pre-select the stopping point for each unit, requires that each center washer be readily adjustable with reference to shaft 17. This is provided in the following manner.

Between sleeve 20 and unit 29 are two large washers 61 and 62 loose on shaft 17. These two washers are spread by a spring washer 63 bent so that this spring washer may be compressed by forcing the two large washers together. Immediately beyond sleeve 20, portion 67 of shaft 17 is mutilated to provide two flats 65 and 66.

Portion 67 of the shaft, is adapted to accommodate the manual adjusting means. As clearly evident in Figure 4, this adjusting means comprises a generally L shaped member 70 whose body portion 71 is provided with an aperture 72. This aperture consists of two straight sides and two curved sides and has the same outline as the shaft with the flats. Since the mutilated portion of the shaft extends to the very end, it is evident that body 71 may be moved over the shaft and be rotatably locked thereto although movable lengthwise along the shaft. L shaped member 70 has a head portion 73 carrying a well 74. Head portion 73 is apertured at 75 so that well 74 provides a through aperture beyond head portion 73.

A cam block 76 has a pair of legs 77 and 78 spaced just far enough apart to straddle the shaft

at the portion where flats 65 and 66 are. Thus, cam blocks 76 may be readily disposed over the shaft and, like L shaped member 70, is rotatably locked to the shaft although freely movable along the same. Cam block 76 has a flat face 79 normally adjacent body portion 71 of member 70. On the other side, cam block 76 has an irregular outline. Thus, the upper portion of this side of the block has a substantially straight plane face 80. The bottom portion of this face of the block is cut away to provide a generally triangular outline 81 as seen from the side of the block. This outline provides two sloping cam faces 82 and 83 along the front portions of legs 77 and 78.

Cooperating with cam block 76 is another cam block 85 having a round aperture 86 therethrough and having a flat rear face 87. The front face of cam block 85 has an upper plane face 88 adapted to cooperate with face 80 of cam block 76 and also has a protruding cam section 89 adapted to cooperate with the correspondingly shaped portion of cam block 76. While aperture 86 of cam block 85 is shown as round, it may be shaped similarly to aperture 72 to rotatably lock cam block 85 to the shaft. However this is unnecessary and would require extreme accuracy in aligning the cooperating cam blocks. It is preferred to have aperture 85 round and large enough so that this second cam block may slip over the shaft and be turned to any position.

Cooperating with the first cam block 76 is an adjusting bolt 90 having a slotted head 91 and a collar 92. Bolt 90 is adapted to cooperate with the threaded aperture 93 extending through the top portion of cam block 76, permitting bolt 90 to be adjusted up and down within the space between legs 77 and 78.

The entire adjusting means is maintained in position on the shaft as shown in Figures 1 and 3 between sleeve 20 and knob 95 threaded or locked on the shaft at the end of portion 67. It is preferred to have enough space between sleeve 20 and

knob 95 so that the portions of the unit as shown in exploded form in Figure 4 have some play on the shaft. Bolt 90 is disposed below top portion 73 of member 70 and the various parts are so proportioned that collar 92 engages top portion 73 while permitting head 91 of the bolt to extend up inside of well 74. Thus as bolt 90 is turned in one direction it tends to pull cam block 76 upwardly as seen in Figure 3. The reaction of cam block 75 on second cam block 85 results in the inclined faces 82 and 83 riding on protruding portion 89 and results in a cam action which tends to separate the two cam blocks. The net result is that by turning bolt 90 in a direction tending to move it down, the cam blocks are spread. Since the second cam block 85 is free to move along the shaft, it reacts against sleeve 20 and forces all the preselecting units tightly against each other. Thus, the various sleeves are tightly clamped and the units are maintained in predetermined adjusted position.

What is claimed is:

In a device of the character described, a shaft, means normally rotatable with respect to said shaft but adapted to be clamped in adjusted position by side thrust, an adjusting member threaded on said shaft and engaging said normally rotatable means to exert side thrust thereon, said adjusting member having a cam face thereon, a second adjusting member having a cam face cooperating with said first cam face, said second adjusting member being disposed on said shaft and having a limited degree of movement transverse to said shaft, a bolt threadedly engaging said second member and extending transversely of said shaft, and a third member disposed on said shaft and having a part engaging said bolt, said third member permitting said bolt to turn and adjust the transverse position of said second member whereby cooperating cam surfaces adjust the transverse dimension of the device.

EDWARD J. MASTNEY.
